BRAIDING MACHINE

Charles M. Bellg, Toledo, Ohio

Application June 6, 1945, Serial No. 597,847

7 Claims. (Cl. 87—43)

1

This invention relates to improvements in braiding machines of the type used for producing woven tubular sleeving or applying wrappings in woven form on electrical conductors.

It is a primary object of the invention to provide a braiding machine of simplified construction which is adapted for operation at a high rate of speed.

In braiding machines of the usual type and construction, the alternate braider tubes or bobbins moving in opposite directions are caused to follow serpentine paths thus rotating around each other, and producing an over and under relation of the strands in the woven sleeving. This requires intricate gear mechanism in order to transfer the tube carriers from an inner to an outer position radially of the machine. This type of movement produces considerable strain in the mechanism which limits the speed of rotation at which the machine may be safely operated.

It is another object of the invention to provide a braiding machine embodying the novel feature of moving one set of strand carrying tubes continuously in a circular path.

Other objects and features of novelty will become apparent during the course of the following description.

A braiding machine embodying the present invention is illustrated in the accompanying drawings in which

Figure 1 is an elevational view of the braiding machine;

Figure 2 is a vertical sectional view of the driving mechanism taken substantially on the line 2—2 of Figure 1;

Figure 3 is a plan view of the braiding turret with certain parts being shown in section;

Figure 4 is a vertical sectional view through the turret taken on line 4—4 of Figure 3; and

Figure 5 is a detail sectional view taken on the line 5—5 of Figure 3.

The present invention resides mainly in a novel braider mechanism included in a turret head indicated generally in Figure 1 of the drawings by the numeral 10. The turret provides support for a plurality of braider tubes 11 or bobbins and is rotatably mounted on a central column 12 formed on a base member 13. Associated with the base 13 is an upwardly extending support 14 which carries at its upper end a take-up 15 or "bull wheel." The bull wheel is mounted with its periphery in alignment with the axial center line of the turret 10 and is adapted to apply and maintain tension on the braided material as it is fabricated.

The wheel 15 is driven in suitable timed rela-

2

tion with the turret 10 through gearing including a worm gear 16 indicated in broken lines on the wheel 15 which meshes with a worm 17 mounted on the upper end of a shaft 18 journalled on the upright member 14. The lower end of the shaft 18 is connected through miter gears 19 with a horizontally disposed shaft 20 which is driven by means of worm and gear connection 21 with the turret drive mechanism shown in Figure 2 and soon to be described in detail.

Referring now to Figures 3, 4 and 5, the turret 10 comprises inner and outer ring members 25 and 26 respectively journalled for rotation on the column 12 and an intermediate ring member 27 mounted between the rings 25 and 26 and also journalled on the column 12 for rotation in the direction opposite to that of the inner and outer rings. This will become apparent presently.

The rings 25 and 26 rotate in a counterclockwise direction indicated by arrows on Figure 3 and together carry one-half of the braider tubes or bobbins 11 and a like number of tubes 11a are carried by the intermediate ring 27 which rotates in the opposite direction.

25 The inner ring member 25 includes a hub 30, a radial base flange 31 having an upstanding rim 32 terminating in a radial horizontally disposed surface 33 on which the tubes 11 are carried. The outer member 26 includes a hub 35, a base flange 36 and an upstanding rim 37 which terminates in a radially inwardly extending surface 38 which is aligned with the surface 33. The surfaces are spaced apart to provide a circular passage 39, the purpose of which will become apparent presently.

30 The intermediate ring member 27 also is provided with a hub 40 disposed between the hubs 30 and 35. A radial base flange 41 formed on the hub provides support for an annular series of tube wells 42 in which tubes 11a of braider yarn 40 are carried. An annular plate 44 adjacent the upper end of the wells on the ring 27 is disposed immediately below the surfaces 33 and 38 of the rings 25 and 26 and is provided with a continuous cam groove 45. The cam is of serpentine 45 or undulating formation and passes alternately around opposite sides of adjacent tube wells 42 crossing beneath the passage 39 between each well.

Means in the form of slide blocks 48 for locking 50 the rings 25 and 26 for rotation together are arranged in recessed slideways 49 in the surfaces 33 and 38. Each block 48 (see Figures 3 and 5) is provided with longitudinal grooves 50 at opposite edges for engaging ribs 51 formed within the recess 49 and carries a cam roll 52 running

in the cam groove 45. It will be noted in Figure 3 that when the tubes 11 are at their extreme inner and outer positions, the blocks 48 are in engagement with both ring members which locks them against relative movement.

Each tube 11 forms a part of a carrier unit which moves radially of the rings 25 and 26 in response to relative movement of the cam 45. Each unit comprises a slide block 55 on which the tubes 11 are supported and which are slidably received in slideways 56 formed in the surfaces 33 and 38. Retainer strips 57 are provided on either side of the slideway for maintaining the unit in upright position. A cam roll 58 on the underside of each block 55 is engaged by the cam 45 to move the block and tube radially in and out in the slideway a sufficient distance to place the block when at the end of each movement, entirely within the limits of either the inner or outer rings and thus leave the passage 39 free and open. A stripping guide 60 on each block 55 is arranged so that an eye formed thereon lies substantially over the center of the tube and guides the strand during the braiding operation. Similar guides 61 are arranged adjacent the wells 42 and extend upwardly through the passage 39 for guiding the strands from the tubes 11a.

The driving mechanism for the turret (Figure 2) includes a motor 65 having a bevel pinion 66 thereon meshing with a ring gear 67 secured to the hub 35 of the outer ring 26. Bearings 68 carry the weight of the turret and are supported on a flange 69 formed on the column 12. Anti-friction thrust bearings 70 between the rings 25 and 26 and between the rings 27 and 26 permit readily moving the ring 27 independently of the rings 25 and 26.

Movement of the intermediate ring in a direction counter to that of the inner and outer rings is accomplished by means of pinions 73 journaled on the column 12 (see Figures 3 and 4) engaging upper and lower ring gears 74 secured respectively within recesses formed in the hubs 40 and 35. Thus it will be noted, rotation of the outer ring member 26 by the motor 65 drives the inner ring 25 through the block connection 48 and through the lower ring gear 74 drives the pinion 73. Rotation of the pinion 73 in mesh with the upper ring gear 74 transmits motion to the intermediate ring in the reverse direction.

As previously mentioned the worm gear and pinion 21 is driven by means of a bevel pinion 76 in mesh with the ring gear 67 and carried on a shaft 77 which also carries the worm 21. A hand wheel 78 may be provided for manually indexing the turret to facilitate setting the filled tubes 11 and 11a in place. The tubes 11a are placed in the wells 42 through openings 79 in the upper surfaces 33 and 38 of the inner and outer rings. The openings 79 are arranged between the recesses 56.

The mechanism just described is adapted for production of materials for various uses including hollow sleeving or tubing or for braiding strands of yarn over a core. Such core material may be wire for electrical uses or cords or strands of either organic or inorganic fibrous material. In operation strands from each of the tubes 11 and 11a are gathered and drawn together over the center of the turret. They may be attached to a leader passing over the bull wheel 15 which serves as a take-up as well as a tensioning device for regulating the angle at which the strands are laid. This also governs the spacing of the

strands whether a tight or loose weave is desired.

As the turret is rotated, the tubes 11 moving in one direction tend to wrap the strands drawn therefrom around a point which lies axially of the turret. An equal number of strands carried by the ring 27 are moved in the opposite direction. By reason of the cam 45 carried by the ring 27 and the cam rolls 58 on the blocks 10 55, the tubes 11 are caused to move longitudinally of the recesses 56. The shape of the cam is such that each tube 11 is moved in alternation with the passage of one of the tubes 11a. The tubes 11a thus moving in a circular path 15 with alternate tubes 11 arranged at either side of the path, produces an over and under arrangement of the strands. Thus each strand serves to lock each adjacent strand in place.

It will be apparent that apparatus of the present type may be constructed to accommodate any number of tubes desired. Also a battery of such machines may be so aligned to continuously apply a plurality of braids over a single core member.

25 It is to be understood that numerous changes in details of construction, arrangement and operation may be effected without departing from the spirit of the invention especially as defined in the appended claims.

30 What I claim is:

1. A braiding machine comprising a base member having a supporting column thereon, a turret mounted on said column for rotation about a vertical axis, said turret comprising inner and outer ring members together providing an upwardly facing surface having a continuous annular slot therein, slide members intermittently locking said rings for rotation together, a cam roll carried thereby, strand supply tube carriers 35 on said surfaces mounted for radial sliding movement from one ring to the other across said slot, a cam roll on each carrier, an intermediate ring member mounted between said inner and outer rings, means responsive to rotation of said inner and outer rings for moving the intermediate ring in the opposite direction, a cam formed on said intermediate ring and engaging said cam rolls, strand supply tubes carried by said intermediate ring and arranged beneath said slot for movement in a circular path, strand stripping guides 40 associated with each supply tube, and means for rotating said turret whereby relative movement of said intermediate ring and cam produces radial movement of said ring locks and said first 45 named tube carriers alternately with the passage of each said second named supply tube therebelow.

2. In braiding machine for weaving tubular sleeving including a rotatable turret, a stationary 60 column supporting said turret, said turret comprising inner and outer spaced ring members and an intermediate ring like member positioned therebelow, each ring like member having a hub portion supported by the hub portion next below, means interconnecting the hub portion of said inner and outer ring members for rotation together in one direction, means operatively engaging said intermediate hub and one of said adjacent ring hubs driving said intermediate hub 65 70 in the opposite direction, strand carrying supply tubes mounted on said intermediate ring member for rotation therewith in a circular path, a second set of strand carrying supply tubes mounted on said inner and outer ring members and moveable therewith, means responsive to the ro-

tation of said turret for moving said second set of tubes radially of the turret whereby said tubes cross and recross the path of said first mentioned tubes, and guide members for each strand carrying tube guiding the strands to the element to be covered.

3. A braiding machine for weaving tubular sleeving as claimed in claim 2 in which the means operatively engaging said intermediate hub and one of said adjacent ring hubs includes hub ring gears meshing with a pinion mounted on the stationary column, and anti-friction means between said hubs enabling free rotational movements of same in opposite directions.

4. A braiding machine for weaving tubular sleeving as claimed in claim 2 in which said inner and outer ring members have multiple radially aligned slots, and slide members reciprocable in said slots, one or more of which always interconnects said rings locking same for positive rotation together.

5. A braiding machine as claimed in claim 2 in which the adjacent peripheral edges portions of said inner and outer ring members have multiple semi-circular cut out portions, said semi-circular sections being in alignment to form circular openings enabling replacement of the strand carrying supply tubes mounted on said lower intermediate ring member.

6. A braiding machine as claimed in claim 2 in which said inner and outer ring members have multiple radially aligned slots, slide members operable radially in some of said slots, one or more of which always interconnects said rings locking same for positive rotation together, and slide blocks operable radially in others of said slots and mounting said second set of supply tubes whereby said tubes cross and re-cross said first mentioned tubes during the rotational movement of said ring members.

7. In a braiding machine for weaving tubular sleeving, a rotatable turret, a support for the turret, means for rotating the turret on the sup-

port, said turret comprising concentrically mounted inner and outer spaced ring members interconnected for rotation in one direction together, an intermediate ring movable in the opposite direction upon rotation of said first named rings, strand carrying tubes mounted on said intermediate ring and movable therewith in a circular path, an undulating cam track on said intermediate ring, the apex of each undulation positioned in radial alignment with one of said strand carrying tubes, a second set of strand supply tubes mounted on said first named rings and movable therewith, mounting means for said second set of supply tubes including cam rolls operatively engaging said cam track, multiple radially aligned slots formed in said inner and outer ring members, guide blocks connected to said cam rolls and operating in said radial slots, said second set of strand supply tubes being mounted on said guide blocks thereby to move said tubes rotationally with said inner and outer ring members and successively back and forth across the path of travel of said first named tubes, and slide members operable in other of said radially aligned slots and guided by cam rolls intermittently locking said rings for rotation together.
